ATTORNEYS

UNITED STATES PATENT OFFICE.

NILS H. ANDERSON, OF MIDDLETON, CONNECTICUT, ASSIGNOR OF ONE-HALF TO
WILLIAM A. LORENZ, OF HARTFORD, CONNECTICUT,
FOR THE INVENTION
TYPE-WRITER PLATEN.

1,235,753,

Specification of Letters Patent.

Patented Aug. 7, 1917.

Application filed May 8, 1914. Serial No. 637,162.

To all whom it may concern:

Be it known that NILS H. ANDERSON, citizen of the United States, and resident of Middletown, in the county of Middlesex and State of Connecticut, has invented certain new and useful Improvements in Type-Writer Platens, of which the following is a specification.

My invention relates to typewriter platens or rolls such as are employed upon writing machines, adding machines and the like, and has for its object to silence the noise incident to the contacting of the type with the platen; further to produce a platen for the above purpose whereby the usual large number of carbons may be produced.

The invention therefore consists in certain features of construction, embodiment of materials and arrangement of parts to form a typewriter platen whereby the amount of noise resulting from the operating of a typewriting machine when fitted with my improved platen, is materially decreased.

Heretofore typewriter platens have for the most part been constructed of cylinders or tubes some of which have been filled with so called deadening material, while others have been provided with layers of felt, rubber, etc. All of these differ in principle from my invention and which as will be noted is made very largely of metal disks or units with suitable layers of insulating materials therebetween.

Referring in detail to the accompanying drawings forming a part of this specification similar characters of reference will be found to designate like or corresponding parts throughout the several figures and of which,

Figure 1 shows a side perspective view of a typewriter platen formed in accordance with my invention.

Fig. 2 is a sectional elevation of one end of the platen shown in Fig. 1.

Fig. 3 is a side elevation of one of the metal disks or units of which my platen is formed.

Fig. 4 is a detached central vertical section through one of the metal and two of the insulating disks, of which my improved platen is formed.

Fig. 5 is a similar elevation of one of the insulating disks used between the metal units.

As before intimated my platen includes

an inner roll which in general external appearance looks very much like that of an ordinary wooden roll such as is commonly used in typewriter platens. My roll, however, is formed very different and largely of metal, but like the wooden rolls before mentioned is provided with a relatively hard rubber covering that I have designated as 10 and which forms the striking pad for the typewriter bars.

The inner or body portion of the roll is built up of a series of comparatively thin metal disks or units 11 which are preferably substantially like that shown in Figs. 3 and 4 said disks being preferably stamped up from sheet metal and include a bridge or spoke member 12 and a series of holes 13. The said holes serve to accommodate the tie rods 14 later to be referred to and of which there are preferably three. These disks are arranged vertically and in alinement, but are insulated one from the other by means of a thin sheet of relatively soft material 15 as for instance felt, paper fiber or other deadening material. In fact I find in some instances it is quite practical to simply plate or coat the metal disks with a covering of soft insulating material as for instance rubber or enamel, in the manner indicated in Fig. 4, the object being to so far as possible, separate the disks one from the other so that each disk or short series will serve to receive the blows of the respective types and in a manner to muffle or retard the sound produced by such contact of the type with the roll.

The object of the spoke member which I have preferably shown as a single cross or bridge piece is to further reduce the noise in that it extends across through the hollow portion of the roll and absorbs and retards the travel of the sound. In assembling the disks I preferably arrange these spokes in triple alinement, that is to say every third one aligns with the next succeeding third one in the series.

The insulating disks referred to are preferably cut in a shape similar to that of the metal disks and like them are provided with holes through which the binding rods pass. A suitable number of these metal and felt disks are assembled and arranged side by side in the manner indicated to form a hollow roll of the desired length whereupon the ends are covered with end caps 16 which

include hubs 17 and centrally drilled holes 18 in which the pintle ends 19 are secured. A single one of these caps is employed to form the respective ends of the rolls and 5 is provided with orifices to receive the binding rods 14 extended through the roll in a way to secure the parts in position and together. The rods are provided each with a screw head 20 on one end that is seated in 10 a countersink of the orifice in the face of one cap and are threaded upon their other ends to engage threaded holes 21 in the cap 16 of the opposite end. When these disks and end caps are assembled in the manner shown 15 they obviously form what appears to be a solid roll including a solid smooth peripheral surface, but which as a matter of fact is hollow inside. The hard rubber covering is adjusted and secured upon the roll to 20 form the complete platen after the roll is made up and secured together by the rods.

Having thus described my invention what I claim and desire to secure by Letters Patent is:

25 1. A noiseless platen for a typewriting machine consisting of an outer cylinder, a laminated skeleton core with a continuous outer surface within and reinforcing the walls of the cylinder, heads at the ends of 30 the cylinder, and means securing the heads and core laminae together.

2. A noiseless platen for a typewriting machine consisting of an outer cylinder, a laminated metallic core within and reinforcing the walls of the cylinder, heads at the 35 ends of the cylinder, and means securing the heads and core laminae together.

3. A noiseless platen for a typewriting machine consisting of a cylindrical covering 40 having a continuous outer working surface, a laminated core formed of metal disks within and backing the covering, heads at the ends of said core, and means extending

through the core and heads for holding the parts together.

4. A noiseless platen for a typewriting machine consisting of a cylindrical covering having a continuous outer working surface, a laminated core formed of perforated metal disks within and backing the covering, 50 heads at the ends of said core, and means extending through the core and heads for holding the parts together.

5. A noiseless platen for a typewriting machine consisting of a cylindrical covering 55 having a continuous outer working surface, a laminated core formed of metal disks and interposed sound deadening material within and backing the covering, heads at the ends of said core, and means extending 60 through the core and heads for holding the parts together.

6. A noiseless platen for a typewriting machine consisting of an integral exterior cylinder formed of hard rubber, a laminated 65 interior cylinder composed of metallic and sound absorbing disks, heads at the ends of the cylinders, and means securing the heads and the laminae of the interior cylinder together.

7. A noiseless platen for a typewriting machine consisting of an integral exterior cylinder formed of hardened plastic material, a laminated interior cylinder formed of a series of closely packed perforated 75 disks, heads at the ends of the cylinders, and means securing the heads and the laminated disks together.

Signed at Chatham in the county of Middlesex and State of Connecticut this 6th day 80 of May A. D. 1914.

NILS H. ANDERSON.
